UNITED STATES PATENT OFFICE.

HERBERT S. MILLS, OF CHICAGO, ILLINOIS.

MOVING-PICTURE MACHINE.

No. 918,883.

Specification of Letters Patent. Patented April 20, 1909.

Application filed October 8, 1908. Serial No. 456,049.

To all whom it may concern:

Be it known that I, HERBERT S. MILLS, a citizen of the United States, residing at Chicago, in the county of Cook and State of Illinois, have invented a new and useful Improvement in Moving-Picture Machines, of which the following is a specification.

My invention relates to improvements in the exhibiting variety of moving-picture machines in which the traveling picture-film works in a casing equipped with means for projecting the succession of pictures upon a screen into the line of vision of an observer through the casing who operates the machine by introducing into it a suitable coin or token for starting its operation.

The object of my invention is to adapt a machine of the class referred to for simultaneous use by a plurality of observers of its subject of exhibition from different viewpoints on the casing while affording to each a full view of the exhibition independently of the other observer or observers, but without affording to any observer a more extended view of the same than is paid for by the consideration represented by the coin or token furnished for operating the machine.

In the accompanying drawings, Figure 1 is a view in side elevation, partly sectional, of a moving-picture exhibiting-machine equipped with my improvements, but showing only parts of the casing of the machine, and illustrating diagrammatically the electric circuits and relative positions of the condensing lenses and lamp to the projecting-lens barrel; Fig. 2 is a broken plan view, partly sectional and with the casing-cover removed, showing the view-obstructing members and the mechanism for operating them; Fig. 3 is an enlarged view, regarded in the direction of the arrow on line 3, Fig. 1, of the setting mechanism for timing the action of the view-obstructing members; Figs. 4 and 5 are enlarged sections taken, respectively, on lines 4 and 5, Fig. 2, showing parts in the positions that such parts occupy when a view-obstructing member is interposed in an observer's line of vision; Fig. 6 is a view like that presented by Fig. 4 and Fig. 7 is a view like that presented by Fig. 5, but each showing parts in the positions they occupy with a view-obstructing member in its inoperative or lowered position.

The top or cover 8 of the casing 9 contains a plurality of observation-openings 10, of which three are shown in the present case,

equipped with vizors or shields 11, these view-points being properly disposed for the accommodation of simultaneous observers to direct the vision upon a screen 12 arranged in the casing to receive the reflections from a mirror 13 disposed in the casing in proper relation to the projecting lens of the film-actuating machine 14. This machine may be of any suitable construction, the one shown being that of United States Letters Patent No. 890,936, dated June 16, 1908, for a moving-picture machine having its drive-shaft 15 geared to an electric motor 16 included in the circuit, hereinafter described, of an electric generator, indicated at 17 (Fig. 1), said circuit also including an incandescent electric lamp, indicated at 18, disposed in line with the condensing-lenses indicated at 19. For the purposes of the present invention the picture-film 20, which is actuated in the usual required manner to travel through the machine 14 with a rapid intermittent motion past the end of the projecting-lens barrel 21, is in an endless coil rotated by the machine 14 to pay out the film from and rewind it upon the coil; and I use for the purpose the film-winder which forms the subject of United States Letters Patent No. 887,431, dated May 12, 1908, involving the horizontal rotary coil-containing casing 22 surmounting the machine 14 and geared thereto to be driven by it for paying out the film from the center of the coil to the machine and rewinding it about the periphery of the coil.

As the aforesaid machine and film-winder are not novel but are fully shown and described in the aforesaid patents, their constructions and operations need not be described in detail herein.

A bar 24 is fastened, at bosses 23 at intervals on its upper side, to the under side of the cover 8 by means of screws 25, this bar being bent to conform to the angular cross-section of the adjacent portion of the casing and its position being between the openings 10 and the edge of the cover. Adjacent to each opening 10 a pair of parallel wings 26 and 27 depend for carrying a swinging view-obstructing member 28 provided with a laterally-projecting finger 128 near its free end. This member is shown in the form of a flat rectangular sheet having upwardly extending stiffening flanges about its outer and lateral edges and extended at its rear end as a narrower tail-piece 29 through which it is

screwed upon a transverse cross-piece 30 (Fig. 2) having an ear 31 depending from one end beyond the adjacent edge of the tail-piece and a similar ear 32 depending from its 5 opposite end, beyond the corresponding edge of the tail-piece, and provided with a projecting notched nose 33 forming a catch for the purpose hereinafter explained. A rock-shaft 34 passes through the ears 31 and 32 10 which are fastened to it by set-screws 35, thereby to unite the member 28 with the shaft, which is journaled in the wings 26, 27 to permit the member to swing between them 15 into and out of the line of vision through the observation-opening 10. A spring-pressed pawl 36, of general bell-crank shape, is pivotally supported on the inner face of the wing 26 and normally engages the catch 33 to hold the member 28 in its vision-obstructing position, its engaging-movement being limited 20 by a shaft 45 encountered by its longer arm, with which is connected a tripping-rod 38, actuated in the manner hereinafter described. The rock-shaft 34 carries on its end which 25 projects beyond the wing 26 a head 39 having a finger 40 extending from one end and carrying near its opposite end a laterally-projecting stud 41 to engage with the curved arm 42 of a spring-pressed pawl 43 of general 30 bell-crank shape, pivoted at its angle to one corner of a shield-shaped plate 44 loosely surrounding a shaft 45 which is journaled in the depending wings and carries to turn with it ratchets 46 in position to be engaged by 35 the pawls 43. This pawl is normally held out of engagement with its ratchet against the tendency of its spring to engage it therewith by the pawl-arm 42 bearing against the stud 41 on the head 39 (Fig. 4). On each 40 loose plate 44 is fulcrumed between its ends a lever 47 normally held, by a spiral spring 48 connecting one of its ends with an ear 49 on the plate, against a stud 50 thereon, the opposite end of the lever carrying a laterally-projecting stud 51 to engage the head 39. 45

As will be understood, a pair of the wings 26, 27 is provided with the described mechanism upon them adjacent to each inspection-opening 10 (Fig. 2); and the shaft 45 is 50 in sections connected by ordinary universal joints, as shown, to enable it to be driven from a single point for actuating each set of the mechanism between a pair of the wings for working the view-obstructing member 28 55 of that set.

For driving the shaft 45 it carries a worm-wheel 52 engaged by a worm 53 on a rotary shaft 54, which inclines downwardly into geared engagement, as hereinafter described, 60 with the driving-shaft 15 of the machine 14, whereby the operation of the machine rotates the shaft 54 to slowly and continuously drive (during the operation of the machine) the shaft 45 by the worm-gear connection 65 between the two shafts.

Bell-crank levers 55 are provided, one for each swinging member 28, fulcrumed at its angle on a plate 56 of insulating material upon the inner wall of the casing, to extend one arm into the path of a finger 128, the 70 other depending arm of the bell-crank having a buffer-head 57 projecting from it into the path of said finger, and this arm extending into position to engage with a pair of gripping electric-contact springs 58 projecting 75 from the plate 56 near an adjustable stop 59 thereon for the bell-crank, thus forming the common "knife-switch."

The line of vision from each inspection-opening 10 to the screen 12 is normally 80 obstructed by a member 28 held in the position illustrated in Figs. 4 and 5 by engagement of the pawl 36 with the catch 33. Upon disengagement of the pawl 36, the member 28 drops by gravity and abuts its finger 85 128 against the buffer 57, the momentum turning the bell-crank to introduce its contact-end between the contact-springs 58 and close the circuit, which is traced as follows: from the positive pole of the generator 17 by 90 a wire w to a contact 58, where that wire joins, at x (Fig. 2), a wire w^1 which connects the three sets of springs 58 at binding-posts on the lower ends of the plates 56. On the upper ends of the plates 56 are binding-posts 95 158 connected by a wire w^2 from which, at x^1 , a wire w^3 leads to the terminal y on the motor 16, the other terminal z of which is connected by a wire w^4 with the negative pole of the generator. The lamp 18 is contained in a 100 branch-circuit formed by a wire w^5 connecting the two motor-terminals y and z . Thus the three bell-cranks 55, which are fulcrumed at the binding-posts 158, are included in multiple in the generator-circuit, so that 105 with any or all of them in engagement with their respective contact-springs 58 the circuit is closed, and it is not opened until they are all cut out of such engagement.

The machine 14 being out of operation, a 110 person desiring to use it starts the motor 16 and trips the pawl 36 to free the member 28 controlling the line of vision through the particular opening 10 selected for observation. Both of these results ensue from inserting a suitable coin or token into a coin-chute 60, one of these chutes being provided adjacent to each opening 10 and leading to a coin-deposit box 61 in the casing. In dropping through the chute the coin or token 115 encounters a pivotal bent lever 62 in its path, working in a slot in the chute and connected with the tripping-rod 38. The momentum of the coin turns the lever out of the path of the coin or token to enable it to pass, and the 120 movement of the lever 62 draws upon the rod 38 to trip the pawl 36 and free the member 28, permitting the latter to drop out of its view-obstructing position to that shown in Figs. 6 and 7. In dropping, the finger 128 130

on said member encounters the buffer 57 and the momentum turns the bell-crank 55 to engage its contact-end with the springs 58 and close the circuit, whereupon the motor 5 operates the machine 14 in the usual manner. While the machine is operating, another person and then a third one, each selecting a different inspection-opening 10, may use the machine by inserting a coin or token into 10 the respective chute to trip the pawl 36 controlled therefrom and effect removal of the respective member 28 out of the line of vision; and the machine continues its exhibition on the endless coil of traveling picture-film until all of the contacts at 58 are opened. The arrangement, however, is, for practical purposes, necessarily such as to bring each member 28 back into its view-obstructing position when the observer has viewed the complete 15 scene exhibited by the film, whether the observation commenced at the beginning or at any later part of the exhibition; and this is effected, by the worm-gear 52, 53 in driving the shaft 45, in the following manner: The moment that a member 28 drops, resultant 20 turning of its supporting-shaft 34 turns the head 39 to remove the stud 41 thereon out of engagement with the pawl-arm 42, permitting the pawl 43, under the force of its spring-pressure, to engage the ratchet 46 continuously rotating in the direction of the arrow on each of Figs. 4 and 6. The pawl 43 being on the loose plate 44, the latter turns with the ratchet carrying 25 with it the lever 47 until the free end of the latter engages the stud 51 thereon with the head 39, which holds the lever sufficiently to cause it to turn on its fulcrum and stretch the spring 48 (see Fig. 6); but the stud 51 is meantime slowly dragged along the edge of the head 39 (bearing against a dead-center) until it reaches the end of the eccentric finger 40, whereupon the recoil of the spring 48 suddenly turns the head back to the normal 30 position in Fig. 4, freeing from it the lever 47 and turning the shaft 34 to raise the member 28 into its view-obstructing position, wherein it is locked by engagement of the pawl 36 with the catch 33. In the rise of the member 28 its finger 128 encounters the arm in its path of the bell-crank 55 with sufficient force to disengage its other arm from the contact-springs 58. In the rise of the member 28 the stud 41 encounters the arm 35 42 and disengages the pawl 43 from the ratchet 46.

Inasmuch as picture-films for the present class of exhibiting-machine vary in length, according to the scenes upon them, and it 40 being a primary purpose of my invention to cause the time of permissible inspection by any observer to terminate when the exhibition of the scene on the film used in the machine is completed, I provide setting means for regulating the time of effecting

complete rotation of the shaft 45 to correspond with that of completing the feed of the entire length of picture-film and, accordingly, for permitting a member 28 to remain in its non-obstructing position. The 45 means referred to are most clearly illustrated in Fig. 3. The inclined shaft 54 is journaled toward its lower end in a bracket 63 on the frame of the machine 14 and carries on its lower end a gear-wheel 64 provided on one 50 face with radial teeth-forming ribs 65 at uniform intervals apart. Midway, both circumferentially and radially, between each pair of the teeth 65, is a shorter rib or tooth 66 bifurcated at its outer end to form two 55 teeth 67, producing three equal spaces between adjacent teeth 65 and adapted to be engaged by the driving-member, hereinafter described. The driving-member 68 is a gear-pinion provided with rounded teeth and 60 carried by a rotary shaft 69 journaled, to extend at a right-angle to the shaft 54, in the frame of the machine 14 and in an arm-extension 163 of the bracket 63, to cause the teeth of the wheel 68 to engage those of the 65 wheel 64 at a right-angle thereto. The shaft 69 is geared, as shown at 169 in Fig. 3, to the drive-shaft 15 of the machine 14. The wheel 68, which is secured to its shaft by a set-screw 170 working in its hub 70, is adjustable longitudinally of the shaft to engage 70 it with the driven wheel nearer to the center of the latter for its greater speed of rotation or farther from said center to reduce that speed. For the purpose of explanation it 75 may be supposed that the adjustment will be used for films respectively of one, two and three hundred feet in length. For timing the endurance of the view-obstructing members 28 in their dropped condition for the 80 longest film the wheel 68 would be set to engage the wheel 64 near its periphery and thus with all the teeth on the latter; for the next shorter film the setting of the driving-wheel would be midway between the center and 85 periphery of the wheel 64 and drive it at twice the speed by engagement only with its teeth 66 and 65; and for the shortest film the wheel 68 would be set, in the position illustrated, nearest the center of the driven 90 wheel, to turn it at three times the speed of the first-named setting by engagement only with its teeth 65. Of course, as will be understood, these relative speeds may be varied, for different relative lengths of picture-films, by properly constructed wheels 64, 68. 95

It will be apparent from the foregoing description that when the operation of the machine is once started it will be continued each time an additional observer, during the operation, uses an unoccupied opening 10 and causes the respective member 28 to drop out of its view-obstructing position, but that each successive observer will have the scene 100 on the film presented to him beginning at an 105

intermediate part thereof, though the exhibition will necessarily continue until the scene is carried to the point at which the observation began.

5. What I claim as new and desire to secure by Letters Patent is:

1. In a moving-picture machine, the combination of a casing containing the picture-exhibiting mechanism, including a reflection-receiving screen, and provided with a plurality of observation-openings directed toward said screen, a view-obstructing member normally extending in the line of vision from each said opening, and means for removing 10 said members, independently of each other, out of the respective lines of vision.

2. In a moving-picture machine, the combination of a casing containing the picture-exhibiting mechanism, including a reflection-receiving screen, and provided with a plurality of observation-openings directed toward said screen, a view-obstructing member normally extending in the line of vision from each opening, means for removing said members, independently of each other, out of the 20 respective lines of vision, and timed means for returning said members, independently of each other, to their normal view-obstructing position.

30 3. In a moving-picture machine, the combination of a casing containing the picture-exhibiting mechanism, including a reflection-receiving screen, and provided with a plurality of observation-openings directed toward said screen, means for obstructing the line of vision from each opening, comprising a rock-shaft carrying a view-obstructing member and a catch-device for normally holding said member in said line, a trip-device for releasing said catch-device to permit said member to move out of said line, a rotary shaft having a worm-gear driving-connection with the drive of said mechanism, and cooperating means for each of said members on said rotary shaft and rock-shaft operating to restore a member to its normal position at the end of a complete rotation of said rotary shaft after the release of said catch-device.

50 4. In a moving-picture machine, the combination of a casing containing the picture-exhibiting mechanism, including a reflection-receiving screen, and provided with a plurality of observation-openings directed toward said screen, means for obstructing the line of vision from each opening, comprising a rock-shaft, a view-obstructing member, a catch and a head on said shaft, a pawl normally engaging said catch to hold said member in its view-obstructing position, a trip-device for releasing said pawl to permit said member to turn from said position, a rotary shaft having a worm-gear driving-connection with the drive of said mechanism, and independently operating means on said rotary

shaft for each of said members for restoring it to its normal obstructing position, comprising a ratchet, a loose plate carrying a pawl to engage the ratchet, having an arm to engage said head, and a spring-pressed lever on said plate to engage said head, for the purpose set forth.

5. In a moving-picture machine, the combination of a casing containing the picture-exhibiting mechanism, including a reflection-receiving screen, and provided with a plurality of observation-openings directed toward said screen, a pair of bearing-wings near each opening, a rock-shaft journaled in each pair of said wings and carrying a catch and a head, a view-obstructing member on each shaft adapted to turn with it, a pawl normally engaging said catch to hold said member in its view-obstructing position, a trip-device for releasing said pawl to permit said member to turn from said position, a rotary shaft formed of jointed sections each journaled in a pair of said wings and having a worm-gear driving-connection with the drive of said mechanism, and means on each shaft-section for restoring one of said members to its normal obstructing position, comprising a ratchet, a loose plate carrying a pawl to engage the ratchet, having an arm to engage said head, and a spring-retracted lever on 95 said plate to engage said head, for the purpose set forth.

6. In a moving-picture machine, the combination of a casing containing the picture-exhibiting mechanism, including a reflection-receiving screen, and provided with a plurality of observation-openings directed toward said screen, view-obstructing members, one for each opening, normally extending in the line of vision therefrom, means for removing said members, independently of each other, out of the respective lines of vision, means for returning said members, independently of each other, to their normal view-obstructing position, a rotary shaft operating said returning means and carrying a worm-wheel, a second rotary shaft carrying a worm engaging said worm-wheel, and a setting-device geared to the drive of said mechanism and engaging with said second rotary shaft for 110 timing its rotation, for the purpose set forth.

7. In a moving-picture machine, the combination of a casing containing the picture-exhibiting mechanism, including a reflection-receiving screen, and provided with a plurality of observation-openings directed toward said screen, view-obstructing members, one for each opening, normally extending in the line of vision therefrom, means for removing said members, independently of each other, out of the respective lines of vision, means for returning said members, independently of each other, to their normal view-obstructing position, a rotary shaft operating said returning means and carrying a worm-wheel, a 125

second rotary shaft carrying a worm engaging the worm-wheel, and a setting-device comprising a gear-wheel on said second shaft having sets of teeth on its face, a rotary shaft 5 geared to the drive-shaft of said mechanism, and a driving-member for said gear-wheel on said last-named shaft and adjustable longitudinally thereof to engage said gear-wheel at different points between its center and periphery, for the purpose set forth.

8. In a moving-picture machine, the combination of a casing containing the picture-exhibiting mechanism, including a reflection-receiving screen, and provided with a plurality of observation-openings directed toward said screen, view-obstructing members, one for each opening, normally extending in the line of vision therefrom, means for removing said members, independently of each other, 15 out of the respective lines of vision, means for returning said members, independently of

each other, to their normal view-obstructing position, a rotary sectional shaft having its sections connected by universal joints and operating said returning means, a worm-wheel on said shaft, an inclined rotary shaft carrying on its upper end a worm engaging the worm-wheel, and a setting-device comprising a gear-wheel on the lower end of said inclined shaft having sets of teeth on its face, 25 a rotary shaft geared to the drive-shaft of said mechanism, and a driving-member for the gear-wheel on said last-named shaft having rounded teeth and adjustable longitudinally of its supporting shaft to engage the 30 gear-wheel at different points between its center and periphery, for the purpose set forth.

HERBERT S. MILLS.
